FURNACE

Walter R. Breeler, Fredonia, N. Y.

Application March 21, 1939, Serial No. 263,169

2 Claims. (Cl. 263—28)

My invention relates to furnaces, and particularly to furnaces of the car or movable hearth type.

Heat, in furnaces of this type, is usually supplied from burners positioned at the top of the furnace or behind bridge walls near the top, and heat distribution is accomplished by the flow of hot gases from the burners through the interior of the furnace to flue outlets in the side walls at about the level of the hearth. In the ordinary type of furnace with the burners projecting through the side walls near the top thereof the hot gases tend to flow from the burners diagonally downward and across the interior of the furnace directly to the flue openings in the side wall opposite the burners, and this path of hot gas flow leaves a more or less cool or "dead" zone in the lower central portion of the furnace. Because of this "dead" zone, an excessively long time is required to heat the bottom and central part of the charge on the hearth and, in many instances, these portions of the charge never are heated to the correct temperature.

In order to produce a more uniform heat distribution, it has been proposed to build a movable hearth having combustion chambers or flues therein running parallel to the front of the furnace. Aligned with the axis of each such flue, is a burner located in the side wall of the furnace and these sources of heat serve to bring the bottom of the charge up to the desired temperature. This arrangement also reduces the time required to heat the furnace.

However, the use of such combustion chambers or flues in the hearth make it necessary to build high piers of fire brick which are so easily broken and so rapidly eroded by the hot gases that, in spite of continual repairs, the life of a hearth of this type is relatively short. Moreover, such flues extending transversely of the hearth weaken the top thereof so that only light charges can be carried.

Another means has been suggested for heating the center of the charge by the use of similar flues in the hearth running parallel to the front of the furnace and connecting with the side wall flues. However, since the movable hearth is really the top of a platform car, and clearance must be provided between the side walls of the furnace and the car in order that it may be moved into and out of the furnace, there is always an open space between the flues in the hearth and the side wall flues.

The principal objects of my invention are to provide a furnace of the car type capable of

handling heavy charges, and in which the charge can be quickly, economically and uniformly heated throughout. I accomplish these objects by means of the novel elements and the combinations and arrangements thereof described below and illustrated in the accompanying drawing in which—

Fig. 1 is a plan view of my furnace with parts broken away to show the interior thereof;

Fig. 2 is a longitudinal vertical section of the furnace; and

Fig. 3 is a section of Fig. 2 in the plane 3—3.

Referring to the drawing, the furnace is represented generally by the numeral 1 and comprises side walls 2, a rear wall 3 and a top 4, the latter preferably being arched as shown in Fig. 3. The front of the furnace is closed by the vertically sliding gate or door 5 provided, at the bottom, with a tongue or projection 6 adapted to fit in a slot 7 in the hearth 8 forming the top of car 9. The hearth or top of the car and the walls of the furnace are formed of refractory material, and the car is provided with the usual supporting wheels 10 which ride on rails 11 so that it may be rolled into or out of the furnace. The interior of the furnace is heated by means of burners extending into or through upwardly inclined tuyères 12 in the side walls of the furnace and which open beneath the arch 4. Between the burners, the side walls are provided with vertically extending flues 13 which communicate with the interior of the furnace at the level of the top of the hearth through openings 14, and the rear wall also is provided with a vertical flue 15.

The hearth or top of the car is provided with a longitudinally-extending, centrally-disposed flue 16 having spaced openings 17 in the top thereof communicating with the interior of the furnace. At the rear of the furnace, the flue 16 communicates with the vertical flue 15 in the rear furnace wall, as shown at 18 in Fig. 2. By this arrangement, it will be apparent that a close connection may be effected between the rear wall flue 15 and the central flue in the hearth merely by pushing the car firmly against the rear wall of the furnace.

In operation, the car, with the charge 19 supported in spaced relation to the hearth on blocks 20, and also having the bars or ingots, illustrated as constituting the charge, arranged in spaced relation to each other, as shown in Fig. 3, so that free circulation of hot gas is provided through the charge, is pushed into the furnace until the hearth abuts the rear wall 3 of the furnace. The open rear end of the flue 16 then registers with

the opening in the back wall of the furnace communicating with flue 15, and the gate or door 5 is lowered to close the furnace as shown in Fig. 2. Hot gases from the burners enter the furnace 5 in the direction shown by the arrows 21 in Fig. 3, and the arrows below the arrows 21 show generally the circulation of the hot gases through all parts of the charge. Some of the hot gases 10 flow over and through the load and out the flues 13 in the side walls, while other currents of hot gas pass downwardly through the charge, through the openings 17 in the top of the hearth, into the longitudinally extending flue 16, and out the flue 15 in the rear wall 3. In this way the hot gases 15 are brought into contact with all parts of the charge which is quickly and uniformly heated thereby.

While I have illustrated only one longitudinal flue in the hearth or top of the car with a plurality of spaced, vertical vents or openings extending therefrom, it is to be understood that more than one flue may be used in the top of the car if desired and that the vents therefrom may, instead of extending vertically, extend in any desirable direction in order to provide proper circulation of the hot gases through the charge.

While I have described my invention in its preferred embodiments, it is to be understood that the words which I have used are words of description rather than of limitation. Hence, changes 30 within the purview of the appended claims may be made without departing from the true scope

and spirit of my invention in its broader aspects.

What I claim is:

1. A furnace of the character described comprising a longitudinally-movable hearth having a longitudinally-extending flue therein communicating with the interior of said furnace through openings in the top thereof, a rear wall having a flue therein communicating with the flue in said hearth, side walls having a plurality of spaced flues therein communicating with the interior of said furnace through openings at about the hearth level, an arched roof on said furnace, and a plurality of upwardly inclined tuyères extending through said side walls and opening into the interior of said furnace near the top thereof for introducing heated gas into said furnace. 10 15

2. A furnace of the character described comprising a longitudinally-movable hearth having a longitudinally-extending flue therein communicating with the interior of said furnace through openings in the top thereof, a rear wall having a flue therein communicating with the flue in said hearth, side walls having a plurality of spaced flues therein communicating with the interior of said furnace through openings at about the hearth level, an arched roof on said furnace, and a plurality of tuyères extending through said side walls and opening into the interior of said furnace near the top thereof for the reception of 20 25 30 fluid burners.

WALTER R. BREELER.
